each designated like characters and modified herein in order to give and develop their best and most effective construction. Like as the vaporizer mentioned above will be used in a refinery structure, it is provided with an automatic flame-spread burner, a flame-spread burner which will always have available a flame spreader and flame-spread burner will be automatically regulated according to the condition of the flame spreader, and will be automatically controlled by the flame spreader.

UNITED STATES PATENT OFFICE

2,381,289

OIL VAPORIZER AND BURNER

Mager C. Jones, Portsmouth, Va.

Application March 10, 1944, Serial No. 525,894

4 Claims. (Cl. 158—91)

This invention relates to new and useful improvements in burners and more particularly to a vaporizer for vaporizing oil in juxtaposition to the burner.

An important object of the invention is to provide a vaporizer which is provided with an automatic air control for supplying air depending upon the volume of oil in the vaporizer.

Other objects and advantages of the invention will become apparent to the reader of the following description.

In the drawings:

Figure 1 represents a top plan view of the apparatus.

Figure 2 is a bottom plan view.

Figure 3 is a vertical section through the apparatus.

Figure 4 is a perspective view of the frusto-conical member.

Figure 5 is a fragmentary perspective view showing the float.

Figure 6 is a perspective view of the operating means for the frusto-conical member.

Referring to the drawings wherein like numerals designate like parts, it can be seen that the apparatus consists of a shell 5 having an upwardly converging side wall and upon which sits a burner bowl 6, the interior of which defines a combustion chamber. The bottom 7 of the shell 5 slants upwardly in an inward direction and merges with a vertically disposed frusto-conical part 8 of the shell 5 having perforations 9 therein. A plurality of props 10 rise from the upper open end of said part 8 to support a flame spreader 11.

The upper end of the frusto-conical part 8 is slightly constricted and provided with a collar 12 for slidably receiving the elongated collar 13 of a vertically disposed frusto-conical slide member 14 which is vertically slidable in said part 8 and as is apparent the lowering of said member 14 increases the space between itself and said part 8 to permit more air to rise and pass through the perforations 9 in said part 8 to vaporize oil in the shell 5, numeral 15 denoting the approximate level of the oil.

The lower end of said slide member 14 is provided with a depending skirt 16 having therein a pair of diametrically opposite slots 17.

Circumscribing and affixed to the upper portion of the skirt 16 is a shelf 18 from which bearing brackets 19 depend to support a horizontal shaft 20 having crank portions 21, 21 located and operative within the slots 17 of the skirt 16.

One end of the shaft 20 has an arm 22 which

is pivotally connected to a rod 23 and this, in turn, extends to pivotally connect to an arm 24 on a rockable structure 25 which includes a float 26 operative in an oil level well 27.

It can now be seen, that depending upon the level of the oil 15, the position of the float 26 will set the shaft 20 and correspondingly the frusto-conical slide member 14 to regulate the amount of air which passes upwardly between said member 14 and the frusto-conical part 8 and into the shell 5 to vaporize the oil content thereof.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. An oil vaporizer comprising a shell said shell having an imperforate outside wall and a bottom forming a container for oil to be vaporized and an inside perforated frusto-conical part rising from said bottom for admitting air through the side thereof into said shell above the level of oil in the shell, means to supply oil to said container, an air admission control member of frusto-conical hollow form vertically adjustable in said frusto-conical part and slidably connected therewith to guide the same during adjustment, and oil level responsive means for adjusting said air control member.

2. An oil vaporizer comprising a shell said shell having an imperforate outside wall and a bottom forming a container for oil to be vaporized and an inside perforated frusto-conical part rising from said bottom for admitting air through the side thereof into said shell above the level of oil in the shell, means to supply oil to said container, an air admission control member of frusto-conical hollow form vertically adjustable in said frusto-conical part and slidably connected therewith to guide the same during adjustment, oil level responsive means for adjusting said air control member, and a flame deflector mounted on the upper end of said frusto-conical part.

3. An oil vaporizer comprising a shell said shell having an imperforate outside wall and a bottom forming a container for oil to be vaporized and an inside perforated part rising therefrom for admitting air through the side thereof to the shell above the level of oil in the shell, means to supply oil to said container, an air admission control member of hollow form vertically adjustable

in said frusto-conical part and slidably connected therewith to guide the same during adjustment, and oil level responsive means for adjusting said air control member comprising a float, a crank-shaft, connecting means between the float and the crankshaft, said crankshaft including a crank operatively connected to said air control member to adjust the same.

4. An oil vaporizer comprising a shell said shell having an imperforate outside wall and a bottom forming a container for oil to be vaporized and an inside frusto-conical perforated part rising

from said bottom for admitting air through the side thereof into said shell above the level of oil in the shell, means to supply oil to said container, and an air admission control member of frusto-conical hollow form in said frusto-conical part provided with a cylindrical end extension slidable through the upper end of the said frusto-conical part whereby said air control member is slidably adjustable in said frusto-conical part, and oil level responsive means for adjusting said air control member.

MAGER C. JONES.
